[57] **CLAIM**

The ornamental design for a work holder for attachment to a step ladder, as shown.

DESCRIPTION

FIG. 1 is a perspective view of the work holder for attachment to a step ladder, showing my new design; FIG. 2 is a top plan view thereof;

FIG. 3 is a rear elevational view thereof;

FIG. 4 is a side elevational view thereof, with both sides views being identical;

FIG. 5 is a front elevational view thereof; and,

FIG. 6 is a bottom plan view thereof.

FIG. 1

FIG. 2

FIG. 3

FIG. 4

FIG. 5

FIG. 6
